VALVE STRUCTURE

Austin R. Baer, Chestnut Hills, Mass.

Application February 27, 1953, Serial No. 339,317

4 Claims. (Cl. 222—394)

2

Fig. 15 is an exploded sectional elevation of the fifth embodiment of the valve structure;

Fig. 16 is a bottom fragmentary plan view of the can;

Fig. 17 is a sectional elevation of the fifth embodiment of the valve structure in assembled position; and

Fig. 18 is a sectional elevation of the valve structure shown in Fig. 17 in dispensing position.

Referring now to the drawings, and particularly to Figs. 1 to 5, a can 1 which contains the goods to be dispensed as, for instance, whipped cream, liquid soap or the like, under gas pressure in a conventional manner, is equipped with an opening 2.

A head member 3, of preferably cylindrical or oval outer shape, has at its bottom a flange formation 4 into which the edge of the can opening tube is inserted in a pressure tight manner. Since the head member 3 is preferably made of rubber or any other similar suitable material, the pressure tight connection between the can opening and the head member 3 may be brought about in an easy manner, namely, by pressing the flange formation 4 over the edge of the can opening 2. The head member is closed at its top and its side wall is formed at one side to greater thickness than the other side, which thick wall formation is adapted to form a base for a sleeve extension 5 of the head member 3. The sleeve extension 5 extends in sideward direction from the head member 3 and starts near the top of the thick wall formation 6 to form a substantially cylindrical tube 7 to extend integrally from the head member 3, so that one portion of the sleeve extension is disposed inside the head member 3 while another portion is disposed outside thereof.

The sleeve extension 5 is adapted to receive a tube 8 of metal, plastic or any other suitable material, the length of which tube 8 is substantially identical with that of the sleeve extension 5. The tube 8 is open at its outer end and closed at its inner end and is equipped near its inner end with an opening 9 disposed at its periphery, which opening 9 normally is pressed against the thick wall formation 6 of the head member, which pressure is brought about by the gas pressure inside the can 1 exerted upon the inner part 10 of the sleeve extension.

The tube 8 may be connected with the sleeve extension 5 by providing a bent-over flange 11 at its outer end, which flange 11 receives the outer end of the sleeve extension 5 (Fig. 1). Instead, providing the flange 11, it is possible to provide a plurality of circular groove formations 12 on the inner side of the sleeve 5, as shown, as a variation, in Fig. 5 of the drawing. The tube 8' is, in this case, equipped with a number of outer ring formations which are received by the corresponding grooves of the sleeve extension 5'.

As indicated above, the opening 9 of the tube 8 will normally be pressed down on the thick wall formation 6 of the head member 3. Upon exerting pressure with one finger on the top portion of the sleeve extension 5 at a point indicated by the arrow 13 in Fig. 3, the sleeve extension 5 and thereby also the tube 8 are pressed in downward direction overcoming the pressure exerted on the inner part 10 of the sleeve extension 5, which brings about a lifting of the tube 8 and thereby of its opening 9 from the thick wall formation 6 and thus establishing communication between the inside of the can and the tube 8. Figs. 2 and 4 indicate the respective positions of the tube 8 in normal and pressed-down position, respectively.

While Figs. 1 to 5 establish a new principle for a simple valve structure designed for the mentioned particular purpose, Figs. 6 and 9 show an embodiment in which the same principle is used, however, with slightly changed structure.

The can 12 is equipped in this embodiment with a preferably pointed edge portion 14² at its top, which edge portion 14² is adapted to be used as pivot point for the

The present invention relates to a valve structure in general and to a valve structure in particular which concerns itself with the dispensing of liquid or semi-liquid material.

Dispensers for whipped cream, liquid soap or the like by means of gas pressure have been proposed before, yet these known structures are rather complicated and expensive in their manufacture.

It is, therefore, one object of the present invention to provide a valve structure substantially comprising two main elements and which lends itself to easy operation by exerting pressure on one of the elements.

It is another object of the present invention to provide a valve structure which comprises a head member which is secured to an opening of a can in a pressure tight manner and a second member, one of the members having at least one small opening normally closed by the other of the said members due to the inner pressure in the can and opened by merely moving the said other member out of its normal position.

It is still another object of the present invention to provide a valve structure which comprises a head member which is secured to an opening of a can in a pressure tight manner and which receives a metal tube having a small opening in a sleeve-like formation thereof, the opening of the metal tube being normally closed due to the inner pressure in the can and being lifted from its position adjacent the said head member by mere pressure exerted on the metal tube.

With these and other objects in view, which will become apparent in the following detailed description, the present invention will be clearly understood in connection with the accompanying drawings in which:

Figure 1 is a sectional elevation of the valve structure; Fig. 2 is a section along the lines 2—2 of Fig. 1;

Fig. 3 is a sectional elevation of the structure shown in Fig. 1 in dispensing position;

Fig. 4 is a section along the lines 4—4 of Fig. 3;

Fig. 5 is a fragmentary sectional view showing a variation of the connecting means between the head member and the metal tube;

Fig. 6 is a sectional elevation of a second embodiment of the valve structure;

Fig. 7 is a sectional elevation of the embodiment shown in Fig. 6 in dispensing position;

Fig. 8 is a sectional elevation of a variation of the second embodiment of the valve structure;

Fig. 9 is a sectional elevation of the embodiment shown in Fig. 8 in dispensing position;

Fig. 10 is a sectional elevation of a third embodiment of the valve structure;

Fig. 11 is a sectional elevation of the structure shown in Fig. 10 in dispensing position;

Fig. 12 is a sectional elevation of the fourth embodiment of the valve structure;

Fig. 13 is a sectional elevation of the embodiment shown in Fig. 12 in dispensing position;

Fig. 14 is a section along the lines 14—14 of Fig. 12;

tube 8². In this embodiment the head member 3² is substantially a tube formation. The flange 4² is secured to the edge of the opening 2² of the can 1² in a conventional air tight manner. The tube 3² is turned in sideward direction to form the sleeve extension 5² which receives the tube 8². The tube 8² is again open at its outer end and closed at its inner end and is also equipped with an opening 9² disposed near its inner end. The opening 9² of the tube 8² will normally be closed by the inner face of the sleeve extension 5². Upon exertion of pressure by a finger on the tube 8² at a point indicated by the arrow 13² in Fig. 7, the outer portion of the tube 8² will be lowered, while its inner portion will be lifted, thereby raising the opening 9² from the inner face of the sleeve extension 5² and establishing communication between the can 1² and the tube 8². Since the sleeve extension is made of rubber or similar suitable material, the lifting of the inner portion of the tube 8² may be brought about with comparatively slight pressure of one finger against the outer portion of the tube 8².

The embodiment shown in Figs. 8 and 9 is a structure similar to that of Figs. 6 and 7, the only distinction being that the embodiment shown in Figs. 6 and 7 requires exertion of pressure on the tube 8² at a point located outside of the periphery of the can 1², while in the embodiment shown in Figs. 8 and 9 the exertion of pressure on the tube 8³ must be applied at a point which is located within the periphery of the can 1³.

The can 1³ is equipped again in this embodiment with a pointed edge portion 14³ to be used as a pivot for the tube 8³. The head member 3³ is also connected with the opening 2³ of the can 1³ by means of the flange formation 4³ in a pressure tight manner and the head member 3³ is turned in sideward direction to form a sleeve extension 5³. The latter receives the tube 8³ which is opened at its outer end and closed at its inner end. While the opening 9³ was disposed in the embodiment shown in Figs. 6 and 7 at the bottom portion of the periphery of the tube 8², in the embodiment of the Figs. 8 and 9 the opening 9³ is disposed on the top portion of the periphery of the tube 8³. The opening 9³ is normally engaging the inner face of the sleeve extension 5³ and upon exerting pressure at a point inside the periphery of the can 1³, indicated by the arrow 13³ in Fig. 9, the inner side of the tube 8³ will be lowered and the opening 9³, thereby, removed from engagement with the inner face of the sleeve extension 5³, thereby, establishing communication between the can 1³ and the tube 8³.

The embodiment shown in Figs. 10 and 11, is designed to provide a closing valve structure for any tube. In order to achieve this end a tube 3⁴ open at its end receives a sleeve extension 5⁴ which is mounted on the end of the tube 3⁴ and extends for an appreciable length beyond this end. The sleeve extension is preferably made of rubber or other similar suitable material and is adapted to receive a second tube 8⁴ open at its outer end and closed at its inner end. Adjacent its inner end an opening 9⁴ is provided at its periphery, which opening 9⁴ normally engages the inner face of the sleeve extension 5⁴. The sleeve extension 5⁴ is equipped with an enlargement 15⁴, which enlargement is disposed on the side of the sleeve extension 5⁴ on which the opening 9⁴ is arranged. The enlargement 15⁴ may be equipped with an opening 16⁴ to provide means for gripping the enlargement 15⁴ in order to move the sleeve extension 15⁴ in the direction of the arrow 13⁴ shown in Fig. 11. The pull exerted on the sleeve extension 5⁴ brings about a removal of the inner face of the sleeve extension 5⁴ from the opening 9⁴ and establishes communication between the tubes 3⁴ and 8⁴.

The embodiment shown in Figs. 12 to 14 comprises again a can 1⁵. The opening 2⁵ receives a vertically disposed tubular extension of the head member 3⁵. The latter is substantially horizontally disposed and is formed to a sleeve 5 which receives a tube 8⁵ of metal, plastic,

or any other suitable material. The vertically disposed tubular extension of the head member 3⁵ has an axial channel 3a⁵ which surrounds the tube 8⁵, so that the pressure present within the can 1⁵ reaches the top portion 5 of the tube 8⁵. The latter has a small opening 9⁵, preferably at its bottom peripheral portion, which opening 9⁵ is normally closed by engaging the inner face of the sleeve 5. Upon exerting slight pressure on the head member 3⁵ at a point indicated by the arrow 13⁵ in Fig. 13 the opening 9⁵ will be freed from engagement with the inner face of the sleeve 5 and thereby establishes direct communication between the inside of the can 1⁵ and the tube 8⁵ for dispensing of material from the can 1⁵ through the tube 8⁵.

Referring now to Figs. 15 to 18, which discloses a fifth embodiment of the present invention, the can 1⁶ has a downwardly tapered formation 1a⁶ at its opening 2⁶ and the lower end of the tapered formation 1a⁶ has a plurality of radially disposed slots 1b⁶ for a purpose to be described later. The head member 3⁶ is substantially vertically disposed in this embodiment and comprises a longitudinal body which on its outer face has an upper half portion with downwardly increasing diameter, to provide at about the center of its length a set-off to assume an appreciably reduced diameter, from which point the outer surface extends downwardly substantially with a cylindrical shape, to form another narrow neck portion and to terminate in a slightly widened portion towards its lower end. The head member 3⁶ has a vertically disposed tubular channel 3a⁶ open at its upper end and terminating short of the lower end of the head member 3⁶, and a plurality of radially disposed channels 3b⁶ extend from the lower end of the channel 3a⁶ in substantially horizontal direction towards the outer face of the head member 3⁶.

The ring member 3c⁶ is inserted into the tapered portion 1a⁶ of the can 1⁶ and the ring member 3c⁶ has an inner diameter which substantially correspond with the outer diameter of the head member 3⁶ at a point where the radially disposed channels 3b⁶ are provided. The ring member 3c⁶ is adapted to receive the lower portion of the head member 3⁶ which is retained in connecting position with the can 1⁶ by engaging the opening of the tapered portion 1a⁶ with the narrow neck portion at the lower end of the head member 3⁶. The length between the neck portion and the set-off portion of the head member 3⁶ is chosen in such manner that upon insertion of the head member 3⁶ into the opening of the tapered formation 1a⁶ of the can 1⁶, the ring member 3c⁶ is subjected to pressure by the set-off portion of the head member 3⁶ and is pressed on the one hand toward the outer face of the tapered formation 1a⁶ and on the other hand toward the cylindrical outer face of the head member 3⁶, thereby closing the radial channels 3b⁶. Upon slight exertion of pressure substantially at a point indicated by the arrow 13⁶ in Fig. 18, the head member 3⁶ will assume a slightly tilted position by turning upon the lower neck as its pivot and free from engagement at least one of the plurality of radial channels 3b⁶, and thereby establishing connection between the inside of the can 1⁶ and the vertical channel 3a⁶, as shown in Fig. 18.

While I have disclosed several embodiments of the present invention, it is to be understood that these embodiments are given by example only and not in a limiting sense, the scope of the present invention being determined by the objects and the claims.

I claim:

1. A valve structure adapted for dispensing goods under gas pressure comprising a hollow body, having a downwardly narrowing tapered formation, the bottom of the latter forming an opening and a plurality of radially disposed slots extending from the said opening upwardly in the said formation, a first substantially vertically disposed longitudinal member having at about its center a set-off to a smaller diameter in the direction of the body

opening and adjacent its bottom a narrowed neck portion, the latter being received in the said opening of the said tapered formation, the said first member having an axial channel open at its upper end and closed short of the lower end of the said first member, a plurality of radially disposed channels extending from the said axial channel to the periphery of the said first member, a second ring-shaped member disposed between the said tapered formation of the said hollow body and the set-off portion, as well as the peripheral portion therebelow of the said first member and closing all said radially disposed channels of the said first member, the distance between the said set-off portion and the lower end of the said first member being chosen in such manner that upon insertion of the said first member into the opening of the said hollow body, pressure is exerted towards the said second member, to provide a good closure of the said axial channels in inoperative non-dispensing position and to open at least one of the said axial channels upon tilting of the said first member upon the said opening of the hollow body as pivot point.

2. A device for dispensing liquid and gaseous material under pressure comprising a hollow body having an inwardly tapered formation, an opening into the body at the inner end of said formation, a head member disposed substantially along the axis of the tapered formation, a set-off on the head member providing a retaining and sealing surface facing the opening into the body, a neck portion and adjacent larger end portion on the head member, said end being slightly larger than the opening in the tapered formation and retained by peripheral engagement with the opening to prevent outward movement of the head member, a sealing ring fitted around the head member above the neck and held in compression by the set-off against the tapered formation, a channel extending through the head from the outer end of the head member to the surface of the head member under the sealing ring, means permitting passage of the material into the tapered formation wherein the contents are sealed by the head member compressing the ring and released by pivoting of the head member about the opening to compress the ring on one side and open the channel on the other, the seal of the set-off against the ring member and the ring against the tapered formation remaining unbroken.

3. A valve structure for dispensing liquid and gaseous

material comprising a hollow can having in one wall thereof a downwardly tapered formation, an opening at the inner end of said formation, a valve head member having a narrow neck portion at its lower end, a set-off on said head member providing a retaining surface facing the opening, a first channel within the head member extending from the outer end of said member along the axis, second channel means below the set-off extending from the first channel to the surface of the head member, a flexible ring member closely fitted to the head member over said second channel means and received within the downwardly tapered formation in the container, said ring member being retained in compression by the set-off from the head member, the head member being retained by the passage of its lower end through the opening in the tapered formation whereby the material in the container passes said opening and is retained by pressure of the set-off forcing the ring member against the container while release of the material is effected by pivoting the head member about the opening to compress the ring on one side and expose the channel on the opposite side permitting the material to flow out through the head member.

25 4. A dispensing container comprising a hollow body having in one wall thereof an opening at the bottom of a downwardly tapered formation, a dispensing valve assembly fitted to said tapered formation comprising a valve head member having a bulbous lower end extending through and held by said opening, a set-off on said head member providing a surface facing the opening, a compressible sealing ring member on the head member adjacent the set-off, and channel means connecting the outer end of the head member to the surface of the head member under the ring whereby the head member is held by the opening and the ring member is retained in compression against the surface of the tapered formation by the set-off on the head member.
